APOLIS SWITCH AND FROG COMPANY, OF SPRINGFIELD, OHIO, A
CORPORATION OF INDIANA.

RAILROAD-SWITCH.

No. 832,631.

Specification of Letters Patent.

Patented Oct. 9, 1906.

Application filed April 26, 1906. Serial No. 313,793.

To all whom it may concern:

Be it known that I, GEORGE S. SHAW, a citizen of the United States, residing at Springfield, in the county of Clark and State 5 of Ohio, have invented certain new and useful Improvements in Railroad-Switches, of which the following is a specification, reference being had therein to the accompanying drawings.

This invention relates to improvements in railroad-switches; and the essential object in view is to provide devices by which the switch-rails may be adjusted to and from each other and relatively to the switch-bar 15 and may be held to different adjusted positions on the switch-bar.

In practice it is found that it often becomes necessary or desirable to shift one or both of the switch-rails on the switch-bar to take up 20 or compensate for the wear or strains which have tended to make the switch-rails improperly fit up against the main rails.

To accomplish this result and to strongly and firmly hold the switch-rails on the switch-bar is the object of my invention.

It consists of the organization and constructions hereinafter fully described, and particularly pointed out in the claims.

In the accompanying drawings, Figure 1 is 30 a plan view illustrating my invention applied to a pair of switch-rails shown in conjunction with a track comprising rails and cross-ties, as usual; Fig. 2, an enlarged partial side view and partial section of my switch device; Fig. 3, a plan view of the same; and Fig. 4, a 35 detail sectional view on the line $x-x$ of Fig. 3, showing the rail-bracket, switch-bar, and adjusting-plate in cross-section.

At 1 is indicated a series of cross-ties supporting the usual main rails 2 and a pair of switch-rails 3, also of the usual construction and adapted to be shifted to and from the main rails at their free ends, so as to perform the usual function of taking the train from 45 the main line off to a siding or from a siding back to the main line. At 4 is shown the switch-bar operated and held by the usual throwing and locking devices, (indicated at 5.) This bar and the manner of using it is as 50 usual with the exceptions now about to be stated.

Referring to Fig. 2, it will be seen that the switch-bar 4 is slotted at 6 and that a bolt 7

is extended through this slot and through a rail-bracket 8, as also through an adjusting- 55 plate 9. By screwing down the nut on this bolt these several parts will be firmly bound together. The rail-bracket 8 is secured to the rail by one or more bolts 10, as clearly shown in Fig. 2, and the adjusting-plate 9 is 60 also secured to the rail-bracket 8 by the bolt 7. For more strongly securing the adjusting-plate by the bolt 7 and for keeping the parts more perfectly in line and together the adjusting-plate is of substantially U shape in 65 cross-section, as shown in Fig. 4, and extends down past one edge of the switch-bar 4 and thence under it, as shown by the part marked 11. The bolt 7 passes through this part also. Then the adjusting-plate 9 ex- 70 tends along the switch-bar a convenient distance, where it is fashioned to fit snugly against the bar, as shown at 12. The upper surface of this part is provided with oblique serrations 13, which are neither in line with 75 the strain on the adjusting-bar nor at right-angles to the line of such strain, but are in a direction which lies between these two extremes, as more clearly seen in Fig. 3. The result is that strains exerted on the adjusting- 80 plate lengthwise of the switch-bar do not pull in line with the serrations, while the movement of the adjusting-plate to effect an adjustment of the rail is also other than lengthwise with the serrations. As a consequence 85 the serrations oppose both movements of the plate, and thus they more firmly hold it, a washer 14, having serrations corresponding in position and size with those on the adjusting-plate, being fitted thereto, as shown in Fig. 2, 90 and held down upon the adjusting-plate by the bolt 15 and its nut. This bolt passes through the opening in the switch-bar 4 and is additionally secured by a brace 16, secured to the switch-bar by rivets 17. When the 95 nut on the bolt 15 is screwed down hard, it forces the serrations of the washer 14 into the serrations 13 of the adjusting-plate and as a result secures the rail-bracket 8 by means of the bolt 7 and in turn secures the rail; but by 100 releasing the nut on the bolt 15 the brace 16 will be eased up, so as to spring away enough to permit the washer 14 to be disengaged from the adjusting-plate. As the bolt 15 extends through an oblique slot 18 in the ad- 105 justing-plate 9, as seen in Fig. 3, it will be

understood that by shifting that portion of the adjusting-plate sidewise it will travel on the bolt 15 through the cam action of the slot 18, and thus move the adjusting-plate 5 bodily lengthwise and adjust the rail back or forth, according to the direction in which the adjusting-plate is so shifted. Of course the nut on the bolt 7 is eased up before this adjustment is attempted, so that it may 10 travel in the slot 6 during the adjustment. Thus it will be understood that with my improved device the switch-rails may be readily adjusted in or out on the switch-bar, while they are also firmly held and secured to the 15 bar after effecting such adjustments. It will be noted that the line of strain on the adjusting-plate should the rail be forcibly struck by a car-wheel with the tendency to move it lengthwise of the switch-bar will be resisted 20 by the oblique position of the serrations, as well as by the oblique position of the slot 18, while the lateral movement of the slotted end of the adjusting-plate is resisted also by the 25 position of the serrations. Thus the adjusting-plate is held firmly both in the line of strain and in the line of movement it would have to assume in yielding to the strains which tend to move it lengthwise.

I claim—

- 30 1. In a switch, the combination, with a switch-bar and a rail, of adjusting and securing devices comprising an adjusting-plate having connection with the rail and bar, means to release the plate from the bar, and 35 means for moving said plate transversely of said bar, when so released, to adjust the plate lengthwise of the bar.

2. In a switch, the combination, with a

switch-bar and switch-rails, of adjusting and fastening devices comprising a bracket secured to the rail, an adjusting-plate secured to the bracket, and means for moving said plate transversely of said switch-bar for adjusting the plate relatively to the switch-bar. 40

3. In a switch, the combination with a switch-bar and a rail, of adjusting and securing devices comprising an adjusting-plate having connection with the rail, and provided with oblique serrations and an oblique slot, a serrated washer engaging with the serrations of the plate, and a bolt passing through the bar, said slot and said washer. 45 50

4. In a switch, the combination, with a switch-bar and a rail, of a bracket secured to the rail, an adjusting-plate secured to the bracket, a bolt to so secure them and on which the plate may swing, the plate having an oblique slot and oblique serrations, a bolt carried by the bar and extending through said slot, and a serrated washer carried by the bolt and engaging the serrations of the plate. 55

5. In a switch, the combination, with a bar and a rail, a bracket secured to the rail, a bolt passing through a slot in the bar and through the bracket, an adjusting-plate held 60 by such bolt and having an oblique slot and oblique serrations, a washer with similar serrations, a bolt passing through the bar and said slot and securing said washer, and a brace to additionally secure said bolt. 65

In testimony whereof I affix my signature in presence of two witnesses.

GEORGE S. SHAW.
